UNITED STATES PATENT OFFICE.

DANIEL B. JACOBS, OF SWAN VALLEY, OHIO.

GARTER.

Application filed March 26, 1924. Serial No. 702,091.

To all whom it may concern:

Be it known that I, DANIEL BRADFORD JACOBS, a citizen of the United States, and a resident of Swan Valley, in the county of 5 Bonneville and State of Idaho, have invented a new and Improved Garter, of which the following is a full, clear, and exact description.

This invention relates to improvements in 10 garters, and has for one of its objects the provision of a garter of simple and practical construction which will effectively support the hose without necessitating the use of an elastic leg encircling band, which has 15 been found to lose its elasticity in a comparatively short space of time, and which oftentimes causes a disagreeable binding action upon the leg.

Another object is to provide a garter 20 which may be produced at a minimum cost and in which the leg encircling band may be used indefinitely by reason of having the hose supporting means detachably connected to the band so that said means, when worn 25 out, may be discarded and replaced thus avoiding the necessity of purchasing a complete new garter.

The above and other objects will appear 30 more clearly from the following detailed description, when taken in connection with the accompanying drawing, which illustrates preferred embodiments of the inventive idea.

In the drawing—

35 Figure 1 is a front elevation of one form of the invention;

Figure 2 is a fragmentary edge elevation of the garter attaching means; and

40 Figure 3 is a perspective view of a link member employed in connection with the garter attaching means.

Referring more particularly to Figures 1 to 3, the garter is shown as comprising a pad 5 made of any suitable material, such as 45 leather or the like, and to which is connected one end of a leg encircling band 6 formed of

a strip of flexible but non-elastic material, said end of the band being looped and extended through a slot 7 in the pad 5 and connected to an adjusting buckle 8 utilized 50 to fit the band to the wearer's leg. The opposite end of the band 6 has attached thereto a suitable link 9 engageable with a stud 10 secured to the pad 5 adjacent one end thereof, said link maintaining the band 55 about the wearer's leg when the garter is in use.

The attaching means, as shown in Figure 1, consists of a coil spring 11, one end of which is detachably engaged with a stud 12 located centrally of the pad 5 while the other end of said spring is connected to one end of a link 13. This link is formed with a cross-piece 14 adjacent said end to which is attached the strap 15 carrying the stud 16. This strap may be made of the same material as the band 6 and the stud 16 carried thereby cooperates with the link 13 in attaching the garter to a sock.

From the foregoing description it will be apparent that the hose attaching means may be detached from the pad of the garter should it become worn to such an extent as to be no longer useful and replaced with a new part thus avoiding the necessity of discarding the entire garter including the leg encircling band.

What is claimed is:

A garter comprising a pad provided with a stud, an inelastic leg band having one end permanently secured to the pad and its other end detachably secured thereto, a spring having one end detachably engaged with the stud of the pad, a link having a transverse slot at its upper end to the upper member of which slot the lower end of the spring is secured, and a strap of inelastic material secured to the lower member of the slot of the link and having a stud at its lower end with which the link engages.

DANIEL B. JACOBS.
